UNITED STATES PATENT OFFICE.

FRANK ERNEST JACKSON, OF MINAS DE RIO TINTO, SPAIN.

KITE-PARACHUTE.

No. 923,181.

Specification of Letters Patent.

Patented June 1, 1909.

Application filed July 2, 1908. Serial No. 441,698.

To all whom it may concern:

Be it known that I, FRANK ERNEST JACKSON, a subject of the King of Great Britain, residing at 4 San Dionisio, Mines de Rio Tinto, Provincia de Huelva, Spain, have invented certain new and useful Improvements in Kite-Parachutes and the Like, of which the following is a specification.

My invention has for its object improvements in kite-parachutes and the like, and particularly the attachments to convey a parachute, balloon or the like, propelled by the force of the wind, supporting a toy figure or other articles (more particularly mentioned hereafter) secured to the parachute or its attachments up a suspended line or cord attached to a kite or kites or other flying device or devices when same are in flight, and to release the said parachute or the like and 20 its attachments from the said line.

The invention is best described by the aid of the annexed sheets of drawings forming a part of this specification, in which similar characters of reference indicate corresponding parts in all the figures.

Figure 1. is a side view of the grooved conveyer fixed on the kite line, or other line, with an arm, connecting ring or balance weight and parachute cords attached to said 30 ring or balance weight. Fig. 2. side view of the opposite side of the conveyer and showing a toy figure attached from suspended arm or rod being hoisted up the kite line or other line by the parachute. Fig. 3. 35 side view of a flat switch or releaser attached to the kite line or other line in position to release the conveyer from the suspended line. Figs. 4, 5, and 6 side views of modifications of the conveyer arranged to reduce friction on 40 the kite line and showing a few variations of attachments. Fig. 7. side view of the conveyer having slid upon the lower part of the switch and about to be thrown into space by the revolute action of the switch. Fig. 8. 45 showing relative positions of the attachments and parachute when in space and returning to earth after being switched from the kite line or other line. Fig. 9. side view of conveyers connected by a frame. Fig. 10. 50 side view of a modification of a switch and a button fixed on the kite line at the lower pointed end of the switch. Fig. 11. front or plan view of the said button. Fig. 12. showing parachute or the like with attach-

ments ascending a kite line and position of same when in space.

The above mentioned result is effected by means of the combination of a conveyer for the parachute or the like in the form of a guiding groove or gutter *a* Fig. 1. (which fits 60 on and is suspended from and slides up or along the kite line *b*) and a switch or turnoff *c*, which is secured to the kite line *b* at any desired point on the said line, and is capable of switching or throwing the conveyer *A*, and 65 consequently the parachute with other attachments from the kite line into space.

The conveyer *a*, is made preferably of thin sheet metal such as tin or other suitable material, and heavier material for 70 strength if required, and is formed by bending over (at or near its longitudinal central part of the widest rounded portion) a piece of said metal cut in a rounded or partially rounded shape, which when thus bent over 75 forms a groove or gutter with one side *d* preferably projecting below the other side *e*, Fig. 2 (but not of necessity) to receive a connecting arm *f*, and all the sides and top guiding edges which come in contact with the 80 switch are made preferably rounded or bell mouthed in shape (but not of necessity) with a sufficient space between the two sides *d* and *e* Fig. 2, and top part of the conveyer to receive the kite cord *b*.

The top sliding portion of the conveyer is made rounded vertically or saddle backed as shown in all the figures. The arm *f* is connected to the longest side of the conveyer to a hole *h*, or other convenient attachment, and is securely fitted in a hooked manner or otherwise and preferably sufficiently loose or free at one or more joints to enable the said arm *f* to move to and fro with reference to the conveyer, as the parachute alters its position in the wind (but not loose of necessity), and the other end of the said arm can be hinged or otherwise connected to a ring *i* as shown at *j* Fig. 1, or can be connected to a ring *k* with a hole as shown at *l*, Fig. 2, or the said arm *f* can be made with one loose joint as shown at *h* Fig. 4, the other end of the arm being made solid with the ring as shown at *m* Fig. 4.

From the arm *f*, Fig. 2, a connecting rod or rods *o*, made of wire or other suitable material is or are suspended from a hole *n* (thus forming a swivel joint) and is connected to a

cross bar p , or other convenient attachment, to which the toy figure q is secured, and the said cross bar p is arranged to revolve on the rod o (or firm if required) as shown at r Figs. 5 2 and 8.

The toy figure can be made of tin or other suitable material, weighted if required, and stamped out in bodied form in two parts and connected at the sides with nibs and slits 10 in usual toy fashion; and the toy figure can be made in one with the cross arm p if desired.

From the suspended rod or rods o , Figs. 2 and 9 other articles can be attached and 15 conveyed up the kite line in place of the toy figure, such as an observation car, fireworks, messages and the like, and in certain cases two or more conveyers are useful connected together by a wire or other frame (as shown 20 in Fig. 9) to hold more steadily banners or signals, a photographic camera or meteorological instruments, and as some of the articles are not required to be switched from the kite line, the action of the switch as a releaser can be stopped by inserting on the kite line at the lower pointed end of the switch a stopper or button as shown in Figs. 10 and 11, and the said switch can be made firm on the kite line by threading the line 25 through three or more holes in the switch.

A modified form of switch is shown in Fig. 10, enabling same to be used from either pointed end. In the construction of toy-parachutes where economy of construction 35 is desired the toy figure q and the rod o can be left out, in such case the ring portion of the attachment i , k , m , and m' to m^4 are made heavier to act as a sufficient balance weight for the parachute.

40 The switch c is made of tin, or other suitable material flat and trapeze form in shape either with or without the angles or corners rounded off, and is secured to the kite line preferably by two holes s , s , at or near the 45 center line longitudinally (as shown in Fig.

3), and the kite line being threaded through the said holes retains the switch in position partially above and below the said line, and the switch can be slid along the line to any part of same as required, and can be weighted below the kite line as shown at t Fig. 7, for the purpose of keeping the switch more steady in the wind, but such weight is not a necessity and can be left off if desired. The shape of the said switch can be varied to a limited extent. 55

The cords u of the parachute or the like are gathered together and can be either tied or secured to the conveyer attachments in various ways as shown in the drawings at v 60 and v' .

The top portion of the parachute is made of paper or fabric, and the cords are sewed, pasted or otherwise attached at convenient parts of the lower edge of the parachute. 65

Having now particularly described and designated the nature of my said invention and in what manner the same is to be carried out I declare that what I claim is—

1. In a traveler for kite or other aerial 70 lines the combination of a wind propelled part such as a parachute or the like, and a slider having a bell mouthed groove to fit the line, and means for connecting thereto an article to be conveyed along the line substantially as hereinbefore described and 75 shown.

2. A releasing switch for kite line travelers consisting of a flat plate having near each end and substantially on its longitudinal central axis, an aperture to receive and fit the line and permit the plate to project above and below the line and also to slide along as well as revolve upon the line, substantially as hereinbefore described and 85 shown.

FRANK ERNEST JACKSON.
